Patented Nov. 2, 1976

242,095

ARMCHAIR

Robert Tillberg, P.O. Box 79, S-260 40 Viken, Sweden

Filed Nov. 6, 1974, Ser. No. 521,378

Claims priority, application Sweden May 7, 1974

Term of patent 14 years

Int. Cl. D6—01

U.S. Cl. D6—37

FIG. 1.

FIG. 2.

FIG. 3.

FIG. 1 is a three-quarter, front, perspective view of an armchair, showing my new design;

FIG. 2 is a side elevational view of the armchair of FIG. 1, showing my new design; and

FIG. 3 is a rear, three-quarter perspective view of the armchair of FIG. 1, showing my new design.

The side of the chair opposite that shown in FIG. 2 is a mirror image of the side shown in FIG. 2.

I claim:

The ornamental design for an armchair, as shown and described.
